UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

CURVED PRINTING-PLATE.

Specification of Letters Patent.

Patented Nov. 7, 1916.

1,203,716.

Application filed July 5, 1913. Serial No. 777,414.

To all whom it may concern:

Be it known that I, JOSEPH S. DUNCAN, a citizen of the United States, residing at Chicago, in the county of Cook and State of Illinois, have invented certain new and useful Improvements in Curved Printing-Plates, of which the following is a specification.

This invention relates in general to printing plates and has more particular reference to sheet metal plates on which the printing characters are struck up from the body of the metal in close simulation of typewriting characters.

One of the primary objects of the invention is to provide a printing plate of this character which will be curved throughout its length transversely to the lines of printing characters thereon to conform to the curvature of an impression cylinder adapted to have a series of such plates secured thereon in close juxtaposition to produce a complete printing form adapted to print a form letter at one operation of the cylinder.

To facilitate an understanding of my invention I have illustrated one embodiment of the same on the accompanying drawings to which the following description relates.

Referring to the drawings—Figure 1 is a plan view of a printing plate embodying my invention; Fig. 2 is an end view thereof; and Fig. 3 is an enlarged fragmentary view taken transversely of the plate.

From the drawings it will be observed that my invention comprises a plate 5, preferably made of sheet metal of sufficient length to accommodate lines of printing characters of the desired length. The lines of printing characters designated by reference character 6 are stamped up from the body of the metal by any suitable machine such, for instance, as a graphotype. A downwardly projecting flange 7 is formed along one longitudinal edge of the plate, said flange being adapted to engage in a suitable recess or channel formed in the face of an impression cylinder to which the plates are secured.

In order that the plate may conform to the curvature of the impression cylinder and fit closely thereto, the plate is curved throughout its length transversely to the lines of printing characters, the curvature being effected by any suitable machine such, for instance, as that disclosed in my copend-

ing application Serial No. 777,415; filed 55 July 5, 1913, preferably after the printing characters have been stamped up on the plate.

In order that a clear and distinct impression may be made by the full face of each printing character, it is essential that the printing face of the character be flat. With this end in view the plate is curved or bent only between the lines of printing characters at the point 8, with the result that the printing faces of the characters are left perfectly flat, each face being disposed tangentially to a curve concentric with the center of curvature of the plate. A clear and distinct impression may, therefore, be made from the 70 flat printing face of each character.

As has been previously stated, a number of plates constructed as above described are secured in juxtaposition upon the surface of an impression cylinder to produce a complete letter form and, in order that the line spacing throughout the form may be uniform, the lines of characters are struck up quite close to the longitudinal edges of each plate. In other words, the aggregate distances that the longitudinal margins of a plate project beyond the marginal lines of printing characters should equal the distance between adjacent lines of characters 75 on the plate. When the plates are then assembled on an impression cylinder it will be manifest that the spacing between the marginal lines of adjacent plates will be equal 80 to the spacing between the lines on the plates, so that uniform line spacing throughout the form will be secured. 85 90

I claim:

A sectional printing element, comprising a metal sheet of relatively narrow width provided with a rearwardly extending flange 95 along one longitudinal edge, and a plurality of longitudinally extending lines of flat-faced printing characters struck up from the body of the metal, said plate being bent between said lines of printing characters, 100 whereby said plate is curved and the printing faces of said printing characters are disposed in planes tangential to a curve concentric to the curvature of said plate.

JOSEPH S. DUNCAN.
